Primary Examiner — Prabhakar Deshmukh*(74) Attorney, Agent, or Firm* — Davis Wright Tremaine LLP; George C. Rondeau, Jr.**CLAIM**

The ornamental design for a chassis for a video game console, as shown and described.

DESCRIPTION

FIG. 1 is a perspective view of chassis for a video game console showing our new design;

FIG. 2 is a front elevational view thereof;

FIG. 3 is a top plan view thereof;

FIG. 4 is a right side elevational view thereof; and,

FIG. 5 is a left side elevational view thereof.

The broken lines represent portions of the design and form no part of the claimed design.

1 Claim, 5 Drawing Sheets---
